UNITED STATES PATENT OFFICE

LEONARD L. RUGGLES, OF WHEATON, ILLINOIS, ASSIGNOR TO AUTOMATIC ELECTRIC INC., OF CHICAGO, ILLINOIS, A CORPORATION OF DELAWARE

TELEPHONE SYSTEM

Application filed August 13, 1926. Serial No. 128,937.

The present invention relates to telephone systems in general, but is more concerned with party line telephone systems. One object of the invention is the production of new and improved arrangements whereby reverting calls may be made in a party-line telephone system in which directors are employed.

Another object is the production of a new and improved arrangement whereby all positions of the station selector used at a party line connector may be utilized when ringing current is connected to alternate contacts in the bank of any one wiper to prevent injurious sparking and short circuiting of the ringing leads as the wiper is moved over its contacts.

Considering now the reverting call arrangement, as is well known, arrangements are provided in the so-called ring-back switches so that when the calling subscriber hangs up, after having set a ring-back switch in such a position that the calling and called party-line stations on the calling line will be signalled alternately, the ring-back switch is locked in its operated position and it holds the previously operated switches until either the calling or the called subscriber removes his receiver, whereupon the locked-up condition is terminated and the ringing current is removed. In case the calling subscriber hangs up before the ring-back switch has been operated, the connection is released in the usual manner, as the locking arrangement does not become effective until after the ring-back switch has been set. Now, when the director system (a register sender system) is applied to a party line telephone system employing ring-back switches, the two systems will not work together unchanged in case the calling subscriber hangs up promptly after dialling the special number required to set the ring-back switch in the desired position, as the director must be allowed a slight time interval to finish sending after the last digit has been registered. Three different arrangements have been evolved for handling the situation. The simplest of these arrangements is the one in which the subscribers are instructed to wait after dialling until a so-

called "hang-up" tone is heard. This hang-up tone is placed on the talking conductors of the established connection at the ring-back switch after the ring-back switch has been set. Then, when the director switches through and is freed after all the digits have been transmitted, the calling subscriber hears the hang-up tone, and when he hangs up the lock-up condition becomes effective.

Another arrangement developed for handling the situation involves the use of a director which will switch through and free itself immediately upon the dialling of a special ring-back prefix. Following the dialling of this prefix, the calling subscriber dials sufficient digits to trunk the call to the ring-back switch and to set the same in the desired position. This arrangement necessitates that the subscriber dial more digits than may be required otherwise, but, on the other hand, he is not compelled to wait and listen for a tone before he hangs up.

The third arrangement developed is slightly more complicated than either of the other two, but is thought to be the best from an operating standpoint. According to the third arrangement, the calling subscriber dials two digits indicative of a ring-back connection, followed by the two digits necessary to set the ring-back switch. When the last digit of the number has been dialled, the connection is locked up by the director. This locked condition is maintained by the director until it has finished setting the ring-back switch, whereupon the director switches through and is freed, terminating the locked condition, after which the connection is maintained by the ring-back switch until either the calling or called subscriber removes his receiver. In connection with this latter arrangement, the trunk circuit has been rearranged to permit the director to bring about the switch-through operation in the trunk circuit with the line and release relays of the trunk circuit deenergized, as the switch-through circuit is normally completed through working contacts of the line relay.

In addition to the foregoing, arrangements have been provided in the director which are applicable to director systems of general use.

for keeping a record of the manner in which the calls are handled. A record is made of the total number of times that the director is seized; a record is made of the total number of times that the director switches through; a record is made of the number of times the director switches through because no dialling takes place after the director is seized or when the delay between successive 10 digits is longer than is permitted; and a record is made of the total number of times that the director switches through when the call is successful as far as the director is concerned.

15 Other objects and features having to do for the most part with the circuit details involved in carrying out the foregoing will appear upon a perusal of the detailed description which is to follow:

20 Referring now to the accompanying drawings comprising Figs. 1-8, Figs. 1-7 are circuit diagrams showing a sufficient amount of equipment in a system embodying the features of the invention to enable the invention 25 to be understood, and Fig. 8 is a layout drawing showing how the various sheets of drawings should be assembled together in order for them to be understood best.

Referring now to Fig. 1, this drawing 30 shows by means of dotted rectangles the office selector OS, the thousands selector M, and the hundreds selector C. This drawing shows also the trunk circuit TC inserted in the trunk line extending from the line switch 35 bank terminals 2-4 to the office selector OS. The director selector DS is shown associated with the trunk circuit TC for the purpose of connecting up an idle director to handle the call when the office selector OS is seized.

40 Fig. 2 shows a party-line connector having access to ten-party lines, one of which is shown in the drawings. The station selector individual to the connector is shown to the right of the connector. This station selector 45 is operated in the usual manner after the connector has been set on the called line to select the particular called station that is to be signalled.

Fig. 3 shows a so-called "ring-back" switch 50 which is used when the calling subscriber desires to converse with another subscriber on the same line to operate the ringers at the two substations alternately.

One of the directors accessible to the director selector DS, Fig. 1, is shown in Figs. 55 4-7. The portion of the director shown in Fig. 4 comprises the input control switch ICS and the output control switch OCS, together with the relays 301 and 302 that control the 60 stepping of the input control switch.

The portion of the director shown in Fig. 5 includes the sending switch SS, the registers or meters 407-410, and the relays 402-406 which have various controlling functions, as 65 will hereinafter appear.

The portion of the director shown in Fig. 7 includes the office register OR that records the two office digits in the regular subscribers' numbers, and the intermediate distributing frame I.D.F. This drawing shows also the special relay 506 that is operated when a reverting call is made so as to adapt the director for holding the connection after the calling subscriber has hung up and until the ring-back switch has been operated.

The portion of the director shown in Fig. 7 includes the thousands, hundreds, tens, and units registers.

Call to Substation 100

It will now be assumed that a calling subscriber, desiring to converse with the subscriber at substation 100, Fig. 2, removes his receiver, and that his individual line switch seizes the trunk line comprising conductors 5-7 at the terminals 2-4. When this occurs, line relay 21 energizes over the calling line and at armature 24 closes a circuit for release 22. Release relay 22 responds and at armature 20 places a ground potential on release 90 trunk conductor 6 so as to maintain the calling line switch operated. At armature 28, relay 22 closes a circuit through relay 32 and stepping magnet 33 of the director selector DS in series, at the same time connecting test wiper 41, at armature 27, to the junction of the said relay and magnet. In case the trunk line upon which the wipers of the director selector DS is standing is idle, relay 32 energizes regardless of the connection made to the test wiper, leaving the trunk line and the director through which it extends. Assuming that this director is busy, a ground potential is encountered on the busy test contact by test wiper 41 and relay 32 is short circuited and does not energize. As a result of this same ground potential, stepping magnet 33 operates in its usual buzzer-like manner to advance the wipers step-by-step in search of an idle director. Assuming that the director reached through conductors 43-46 is the first one found to be idle, the wipers 39-42 come to rest on the bank contacts to which these conductors are connected, and relay 32, being no longer short circuited, now energizes 105 in series with stepping magnet 33. At armature 36, relay 32 disconnects test wiper 41 from the test circuit and connects it to ground through the working contact and armature 28, making the seized director busy. At 110 armature 37, relay 32 prepares the combined impulse and switching circuit, and at armatures 34 and 35 it connects the conductors 5' and 7' leading to office selector OS to the corresponding conductors 43 and 44 of the seized director. Responsive to this latter operation of the line relay of the office selector OS energizes over conductors 43 and 44 and the selector is prepared for operation in the usual manner. Polarized relay 452, Fig. 5, is in-

cluded in the circuit of the line relay of the selector OS, but relay 452 is not operated at this time owing to the way in which it is polarized.

5 In the seized director, release relay 404, Fig. 5, energizes over conductor 45 and through the resting contact and armature 415 responsive to the grounding of conductor 45 at armature 36 of relay 32, Fig. 1. At armature 417, relay 404 removes ground from restoring conductor 304, and at armature 418 it removes ground from the release conductor 430.

10 The calling subscriber may now proceed to call the various digits in the desired number. To do this, he first dials two digits indicating the office in which the desired line terminates, and then follows with four digits indicative of the line, and a stations digit to indicate 15 the station on the line, as the substation 100 is a party-line substation. It has been assumed that the bank contacts 501, Fig. 6, are the ones assigned to the local office. Accordingly 20 the digits dialled are those necessary to bring 25 the wipers 523 of the office register into engagement with the bank contacts 501.

20 When the first digit is dialled, line relay 21, Fig. 1, falls back a number of times corresponding to the number of interruptions 25 produced in its circuit at the calling substation. Each time it falls back, it closes at armature 25 a circuit through the working contact and armature 26, armature 37 and its working contact, wiper 42 and the bank 30 contact on which it is standing, conductor 46, armature 414, Fig. 5, and its resting contact, conductor 303, series relay 301, Fig. 4, lower wiper of the input control switch ICS and its first bank contact, the corresponding conductor, and vertical magnet 504 of the office 35 register OR to battery. By its operation, vertical magnet 504 raises the wipers 523 step-by-step until they come to rest opposite the desired level of bank contacts. Relay 301, 40 Fig. 4, operates in series with the vertical magnet when the first impulse is transmitted, and, being slow acting, remains operated throughout the series of impulses. At its upper armature, relay 301 closes a circuit for relay 302, and relay 302 operates and prepares a circuit for the operating magnet of the input control switch, which circuit is momentarily closed at the end of the series of impulses when relay 301 falls back and pending the falling back of the slow acting 45 relay 302. When the operating magnet of the input control switch is momentarily energized, the wipers of this switch are advanced one step; and the impulse conductor 50 is shifted from the vertical magnet of the office register to the rotary magnet 505.

50 When the second digit is dialled, the impulses of current are transmitted over the circuit path above traced as far as the lower 55 wiper of the input control switch, from which

point the impulses are delivered to the rotary magnet 505, Fig. 6. As a result, the rotary magnet 505 operates and the wipers 523 are advanced step-by-step until they come into engagement with the bank contacts 501. The wipers of the input control switch ICS are advanced another step at the end of the second digit in the manner above pointed out. The result is that the impulse conductor is shifted over to the operating magnet 70 of the thousands register Fig. 7, and that at the upper wiper of the input control switch ICS a starting circuit to be hereinafter referred to is closed.

75 When the thousands digit is dialled, the thousands register, Fig. 7, is set to register the digit; the hundreds register registers the hundreds digit when it is dialled; the tens and units registers register the tens and units digits, respectively; and the stations 80 register registers the digit dialled to indicate the particular station desired on the party line, the input control switch ICS being advanced one step at the end of each digit.

85 Returning now to the point at which the input control switch advances into its third position at the end of the setting of the office register, the upper wiper of the input control switch connects ground to the lower wiper 90 of the switch ICS and through the associated interrupter to conductor 305, whereupon impulses are delivered over conductor 305 and through the resting contact and armature 423 to the stepping magnet 427 of the sending switch SS. Upon the first deenergization 95 of magnet 427, its back-acting armature advances the wipers 428 and 429 by means of the usual pawl-and-ratchet arrangement one step, and wiper 428 encounters a grounded 100 bank contact, closing a circuit for pick-up relay 405. At armature 420, relay 405 grounds release trunk conductor 45 at a second point so as to prevent the release of the director while the sending switch SS is off 105 normal; it removes at armature 419 a shunt from around sending contacts 425; and at armature 421 it closes a circuit through armature 424 and its resting contact, and including conductor 309, for back-acting magnet 110 of the output-control switch OCS, Fig. 4. As a result of the removal of the shunt at armature 419 from around the sending contacts 420, each subsequent energization of magnet 427 results in an opening of the 115 bridge across the conductors 43 and 44, the wipers 428 and 429 being advanced one step at the end of each interruption of the current flow. At the end of the first interruption, wiper 429 encounters the first impulse 120 stop conductor and it is advanced over the successive stop conductors as the other interruptions are produced and terminated. Since the single office digit necessary in the 125 present case to operate the office selector OS 130

to the third level in order to extend the connection to a thousands selector such as selector M, Fig. 1, is the digit 3, the first office register contact in the group 501, Fig. 6, is cross connected on the intermediate distributing frame I.D.F. to the third impulse-stop conductor, thereby grounding this conductor, as the first wiper 523 of the office register OR is normally grounded through the lower wiper of the outgoing control switch OCS. Therefore, when wiper 429 encounters the third impulse-stop conductor at the end of the third interruption in the outgoing control circuit, a circuit is closed for stop relay 406, Fig. 8. Relay 406 energizes and places a shunt at armature 422 around the sending contacts 426; opens the interrupter circuit of magnet 427 at armature 423 and closes a local restoring circuit through self interrupting contacts 425; and at armature 424 it removes ground from conductor 309 and closes a self-locking circuit. As ground is now removed from conductor 309, the stepping magnet of the switch OCS falls back and advances the associated wipers one step. As only one office digit is needed, the remaining bank contacts in the group 501 of the office register OR, Fig. 6, are cross connected to the skip conductor 310, and a circuit is closed over conductor 310 and through the self-interrupting contacts of the switch OCS for its stepping magnet, automatically advancing the wipers of the switch OCS through the second, third and fourth positions. The advance of the switch ceases when the lower wiper lands on its fifth bank contact.

As a result of the closure of the local restoring circuit for the stepping magnet 427 of the sending switch SS, this stepping magnet operates through the self interrupting contacts 425 and through the restoring wiper 428 and restores the switch SS to its normal position, opening the circuit of the slow acting pick up relay 405. Pick-up relay 405 falls back after a short interval and opens the locking circuit of relay 406 at armature 421. Relay 406 falls back at the end of a further interval and starts the sending switch SS to transmit the thousands digit of the number, unless the thousands register is still in its normal, in which case relay 406 remains operated through the normal contact of the thousands register wiper until such register is operated, as may be seen from an inspection Figs. 5 and 7.

When the sending switch SS operates to transmit the thousands digits, this digit is terminated, in a manner similar to the described termination of the single office digit, when stop relay 406 pulls up over the stop conductor grounded by the wiper of the thousands register; the remaining digits being similarly terminated in accordance with the setting of the remaining registers, respec-

tively. It will be understood of course that the wipers of the outgoing control switch OCS are advanced one step, as described, at the end of the transmission of each digit.

When the wipers of the outgoing control switch are advanced at the end of the retransmission of the stations digit, the lower wiper of the switch closes a circuit through its last bank contact and over conductor 308 for switching relay 403, Fig. 5. Relay 403, at armature 414 disconnects conductor 46 from conductor 303 and connects it to ground, ceasing a switch-through circuit to be mentioned subsequently, and at armature 415 opens the circuit of relay 404. Release relay 404 falls back and closes at armature 417 a restoring circuit over conductor 304 for the outgoing control switch OCS, and closes at armature 418 a release circuit over conductor 430 for the input-control switch ICS, the office register OR and the five registers shown in Fig. 7. Accordingly, the switches mentioned are restored to normal.

As a result of the above mentioned grounding of conductor 46 at armature 414 of relay 403, a circuit is closed over conductor 46 through a wiper and relay contact of the director selector DS, Fig. 1, armature 26 and its working contact, and armature 25 and its working contact for switching relay 23 of the trunk circuit TC. Relay 23 locks itself to conductor 6 at armature 30, and at armatures 29 and 31 disconnects conductors 5 and 7 from the windings of relay 21 and connects them to the corresponding conductors 5' and 7' leading to the office selector OS. Line and release relays 21 and 22 now fall back and release relay 22 frees the director by releasing the director selector DS at armature 28.

When the director is freed, the switching relay 403, Fig. 5, falls back.

Considering now the effect produced by the trains of impulses sent out by the director, the transmission of the office digit 3, results in the operation of the office selector OS, Fig. 1, which raises its wipers opposite the third level and selects an idle trunk line, for example, the trunk line extending to the thousands selector M.

When the thousands digit is retransmitted the selector M responds and extends the connection to a hundred selector in the corresponding group, for example, the hundreds selector D; when the hundreds digit is sent the hundreds selector D responds and extends the connection to an idle connector in the corresponding group, for example, the connector shown in Fig. 2, and reached by way of conductor 91-93.

When this connector is seized, line relay 101 pulls up over conductors 91 and 93 and closes at armature 121 a circuit for release relay 103. At armature 125 release relay 103 opens a point in the release-magnet circuit

and prepares the operating-magnet circuit; it prepares the busy-locking circuit and switching-relay-test circuit at armature 124; prepares the ringing-return circuit at armature 123; and at armature 122 it places ground on conductor 92 to maintain the preceding switches operated.

When the tens digit is retransmitted by the director, line relay 101 falls back momentarily a corresponding number of times and each time it does so it closes at armature 121 a circuit for vertical magnet 109, the circuit at the time of its first closure including armature 125 and its working contact, contact of off normal spring 112 and said spring, and series relay 104. By the operation of vertical magnet 107 the wipers are positioned opposite the level of contacts in which the called line terminates. Series relay 104 operates on the first impulse, and, being slow acting, remains operated throughout the entire series. At armature 126, relay 104 opens a point in the rotary-magnet operating circuit and prepares a new circuit for itself and for the vertical magnet, which comes into play as soon as off-normal springs are shifted as they are upon the first vertical step of the switch.

At the end of the vertical movement, relay 104 falls back and shifts the operating conductor at armature 126 to the rotary magnet operating circuit.

When the units digit is received each impulse delivered by line relay 101 at armature 121 and its resting contact is transmitted to rotary magnet 113, the circuit including armature 125 and its working contact, off-normal springs controlled by spring 112, armature 126 and its resting contact, resting contact and armature 133, and armature 144 and its resting contact. By the operation of rotary magnet 113 the wipers 146-148 are rotated into engagement with the terminals of the desired party line. The slow acting relay 107 operates in multiple with the rotary magnet 113 and remains operated throughout the entire rotary movement. At armature 138 relay 107 disconnects test wiper 147 from the upper winding of relay 108 and connects it through the resting contact and armature 142 to busy relay 106, and at armature 139 it places a shunt around the resting contact and armature 133 so as to maintain the rotary-magnet operating circuit intact regardless of any operation of busy relay 106 that may occur due to the encountering of busy test contacts by test wiper 147 during the rotary movement.

At the end of the rotary movement, busy relay 106 is not operated if the line is idle, but is operated over test wiper 147 if the line is busy. In the latter case a locking circuit is completed for relay 106 including at armature 132 and its working contact when armature 148 falls back. Also, armature 133 holds the

rotary magnet operating circuit open after armature 139 is restored when relay 107 falls back. The usual busy signalling tone is transmitted back over the established connection to the calling substation through the connection established at armature 135 with the common busy signalling apparatus, the calling subscriber being instructed to replace his receiver and release the party established connection when he hears this busy tone.

Assuming now that the desired line is idle when called, busy relay 106 is not operated when the wipers 146-148 come to rest on its terminals, and, when relay 107 falls back, a circuit is completed at armature 138 for the upper winding of relay 108 through test wiper 147. This circuit includes armatures 124 and 132, and is completed to battery through the cut-off relay 149 of the called line. Relays 149 and 108 energize in series over this circuit and relay 149 clears the called line of its normal attachments.

In the connector, relay 108 closes a locking circuit for its lower winding at the lightly adjusted armature 143; at armature 144 shifts the operating conductor from rotary magnet 113 to the operating magnet 162 of the station selector; armature 141 shunts its test winding by placing ground directly on test wiper 147 at armatures 140 and 145 connects up wipers 146 and 148 so as to prepare the ringing circuit.

When the station selecting digit is received, the impulses of current from armature 121 and its resting contact of line relay 101 are delivered through armature 144 and its working contact, of relay 108, to the operating magnet 162 of the station selector. Accordingly, the wipers 164 and 165 are set on the corresponding set of bank contacts, in this case the first set, as the called station has a 66 cycle ringer connected between the negative line conductor and ground. Relay 107 is operated in multiple with the operating magnet 162 and it maintains a branch circuit of relay 106 open at armature 137. At the end of the operation of the station selector, relay 107 falls back and at armature 137 completes a circuit for relay 106 including off-normal contacts 161 of the station selector. At armature 133, relay 106 opens the operating circuit; at armature 134 it prepares a circuit for release magnet 163; it connects up the wipers 164 and 165 of the station selector at armatures 130 and 136; completes at armature 131 the connection between conductor 167 and the upper winding of relay 105 and including armature 153 and its working contact; and at armature 135 it connects the lower talking conductor through armature 144' and its working contact to the ring-back-tone conductor 166, which conductor connected is the regular 16-cycle ringing lead. Accordingly the calling subscriber hears the tone and

knows that the called station is being signalled.

- 66-cycle ringing current passes to the negative conductor of the called line through the 5 first bank contact and wiper 164, working contact and armature 130, resting contact and armature 127, armature 140 and its working contact, and wiper 146 and the bank contact on which it is standing, a return path to 10 ground from the positive conductor being provided through the positive bank contact and wiper 148, working contact and armature 145, armature 129 and its resting contact, armature 136 and its working contact, wiper 15 165 and the first associated bank contact, conductor 167, working contact and armature 131, armature 123 and its working contact and the upper winding of relay 105. There 20 is no current flow over this return path at this time, however, owing to the fact that the 25 ringers on the party line are connected in ground return circuits. The ringing current is intermittently applied to the ringing conductors by interrupter relay 252, Fig. 3, which relay is controlled by the interrupter 251, the 30 ringing leads being connected to battery during the silent period so as to permit the ring-cut-off relay 105, Fig. 2, to be operated during the silent period.
- When the called subscriber responds by removing his receiver, he bridges the conductors of the called line with his receiver, transmitter, and calling device in series, whereupon 35 a flow of current takes place over the above-traced return circuit, energizing relay 105. At armature 128, relay 105 closes a locking circuit for its lower winding, and at armatures 127 and 129 it disconnects the wipers 146 and 148 from the wipers of the station 40 selector and connects them instead to the usual talking circuit of the connector including the battery feed relay 102. Talking battery is now supplied to the called station through battery feed relay 102, the talking 45 battery for the calling station being supplied through line relay 101. The calling and called subscribers may now converse with each other.
- When the conversation is over, the sub- 50 scribes replace their receivers. When the receiver is replaced at the calling substation, line relay 101 of the connector falls back, opening the circuit of release relay 103 and preparing the release magnet circuit. When 55 release relay 103 falls back it removes ground from release trunk conductor 92 at armature 122, whereupon relays 105 and 108 fall back. At the same time, ground is removed from the 60 busy relay locking circuit at armature 124, and the upper winding of relay 105 is disconnected from conductor 167 at armature 123. At armature 125, relay 103 closes a circuit 65 through off normal contacts 111 for release magnet 110 and through armature 134 and its working contact for release magnet 163.

When these release magnets operate the connector and the station selector are restored to normal position in the usual manner. The circuit of release magnet 110 is opened at off-normal contacts 111 when the connector is restored to normal, and busy relay 106 falls back when its circuit is opened at off-normal contacts 161 and opens at armature 134 a circuit of release magnet 163.

As a further result of the removal of the 75 ground potential from release trunk conductor 92, the selectors OS, M and C, as well as the calling line switch are released in the usual manner, and relay 23 of the trunk circuit TC falls back.

From the foregoing description it may be understood that when any other station on the party line shown in Fig. 2 is called the connector is set in the same position as before, but the station selector is set in some 85 other position, depending upon the particular substation called, the arrangement being such that the selected ringing current is applied to the negative side of the called line if the station selector is set in any odd-numbered 90 position, while the ringing current is applied to the opposite side of the line if the station selector is set in any even-numbered position. By this arrangement, the ringing leads are not connected to adjacent contacts in the bank 95 of either wiper. The conductor 167 is opened at armature 123 of release relay 103 before the releasing operation starts so that there is no possibility of arcing at the bank contacts upon the return of the wipers 164 and 165, 100 as would ensue if the conductor 167 were left connected up, or if adjacent contacts were connected to different ringing leads.

Handling a reverting call

It will now be assumed that a calling party-line subscriber desires to converse with another subscriber on the same line. It will be assumed for the sake of illustration that the ringer of the calling station is a 50-cycle 110 ringer connected between the negative side of the line and ground and that the ringer of the called station is a 66-cycle ringer, also connected between the negative side of the line and ground. Accordingly, when the connection to the reverting call switch is finally established, the reverting call switch must apply 50 cycle ringing current and 66 cycle ringing current alternately to the negative side of the line, as the reverting-call 115 or ring-back switch shown in Fig. 3 will do when its wipers are set upon the first set of bank contacts in the level shown in the drawings. In order to establish the desired connection, the party line subscriber removes 120 his receiver and then dials two digits common to all reverting calls, followed by the two digits required to set the ring back switch in the position necessary to give the combination of rings needed for a particular call 130

being made, after which he replaces his receiver, as he is instructed to do. It will be assumed that the line switch of the calling line selects the trunk line extending to the 5 trunk circuit TC, Fig. 1, and that the director selector DS selects the director shown in the drawings. Accordingly, this director is prepared for operation in the manner hereinbefore described.

10 When the calling subscriber dials the prefix assigned to the reverting call numbers, the wipers 523 of the office register OR, Fig. 6, are raised opposite the proper level and are rotated into engagement with bank contacts 15 502, whereupon the sending operation is started in the manner hereinbefore described.

When the calling subscriber dials the following two digits that are to control the setting of the ring back switch, these digits 20 20 are registered on the thousands and hundreds registers shown in Fig. 7.

When the lower wipers of the switch ICS is grounded by the upper wiper of ICS at the end of the second digit a circuit is closed 25 through the first wiper 523 of the office register, the bank contact on which it is standing, the corresponding I.D.F. jumper, and over conductor 527 for relay 506. Relay 506 energizes and locks itself to release trunk conductor 46 at armature 509; opens the impulse wire leading to the magnet of the tens register Fig. 7, at armature 511; prepares a short-number switch-through circuit at armature 507; and at armature 510 connects the 30 grounded conductor 527 to conductor 528, extending ground through the associated I.D.F. jumper to the third impulse stop conductor. At armature 508, relay 506 prepares a locking circuit for maintaining the seizure 35 of the director independent of the maintenance of current flow over the calling line. 40 This circuit is completed between ground and conductor 46 when the hundreds register goes off normal.

45 When the calling subscriber hangs up his receiver after having finished dialling, relays 21 and 22, Fig. 1 fall back, and relay 22 removes ground at one point from relay 32 and conductor 46, leaving conductor 46 grounded 50 through the above mentioned locking circuit including armature 508, Fig. 6 and off normal contacts of the hundreds register, Fig. 7. As 55 ground from the first contact in the set 502 of the office register Fig. 6, is extended to the third impulse stop conductor over conductors 527 and 528, and as the second and third contacts are cross connected on the I.D.F. to the sixth and fourth impulse stop conductors, 60 the three digits 3, 6, and 4 necessary to trunk the call to a ring back switch are transmitted in the usual manner, after which the outgoing control switch OCS (which has advanced one step at the end of the transmission of 65 each digit) advances another step and arrives

in its fourth position. The fourth code-digit position is skipped in the usual manner.

The director now retransmits the digits registered on the thousands and hundreds registers, Fig. 7, the outgoing control switch being advanced one step at the end of the retransmission of each digit. As a result, the outgoing control switch lands in its seventh position at the end of the retransmission of the digit stored on the hundreds register. 70 When this occurs, the lower wiper of the outgoing control switch prepares a circuit through its seventh bank contact and the associated conductor, armature 507 of relay 506 and its working contact, conductor 308', and 80 the resting contact for the switch-through relay 403, Fig. 5. This circuit is held open at armature 461 for an interval to give the ring-back switch time to switch through. When this circuit is closed, relay 403 energizes and 85 closes a locking circuit for itself at armature 415, at the same time opening the circuit of release relay 404 with results similar to those described hereinbefore. As a further result of the energization of relay 403 a circuit similar to that hereinbefore traced is closed at armature 414 for the switching relay 23, Fig. 1. 90 However, since the calling subscriber has already replaced his receiver, according to the foregoing assumption, and since relays 21 and 95 22 are deenergized as a result, the circuit includes armature 26 and its resting contact instead of armature 26 and its working contact and armature 25 and its working contact. When relay 23 operates it locks itself to release 100 trunk conductor 6 at armature 30, and at armatures 29 and 31 switches the conductors 5 and 7 to the corresponding conductors 5' and 7', at the same time disconnecting the latter conductors from the outgoing control 105 circuit of the sender.

In the director, when the hundreds register is released responsive to the grounding of conductor 430 by release relay 404, the off-normal contacts of the hundreds register remove 110 ground from release trunk conductor 46 to which a ground connection has been maintained through armature 508 and its working contact, as above pointed out. When this occurs, switching relay 403, Fig. 5, and relay 115 32, Fig. 1, fall back and the director is free to handle another call.

The effect of the digits sent out by the director will now be considered. The office selector OS responds to the first code digit 3 120 and seizes a thousands selector such as M; the seized thousands selector responds to the second code digit 6 and seizes a hundreds selector such as C; and the seized hundreds selector responds to the third code digit 4 and 125 seizes an idle ring-back switch such as the one shown in Fig. 3. When such ring-back switch is seized, line relay 203 operates over conductors 94 and 96 and closes at armature 228 an energizing circuit for release relay 130

204. Release relay 204 prepares the switch for operation at armature 230 and 231; and at armature 229 places ground on release trunk conductor 95 so as to hold up the preceding switches.

As a further result of the seizure of the ring-back switch, a circuit is closed for relay 202 responsive to the application of ground potential to conductor 95, which circuit includes the normally closed off-normal contacts 213. At armature 225 relay 202 prepares a locking circuit for itself, and at armature 226 it switches the associated operating conductor from the rotary magnet 211 to the vertical magnet 210.

When the digit registered on the thousands register, Fig. 7, is retransmitted in the manner hereinbefore explained, line relay 203, Fig. 3, falls back each time its circuit is interrupted by the director, and each time it falls back it closes a circuit for vertical magnet 210 at armature 218. This circuit includes armature 231 and its working contact, armature 239 and its resting contact, and armature 226 and its working contact. By the operation of the vertical magnet, the wipers of the switch are raised opposite the desired level of bank contacts. Series relay 208 is connected in multiple with vertical magnet 210 at this time and it operates and remains operated throughout the series of impulses on account of its slow-acting characteristic. At armature 240, relay 208 completes a locking circuit for relay 202 including the working contact and armature 225, before the initial circuit of the relay is opened at off normal contacts 213, as it is upon the first vertical step of the switch.

At the end of the vertical movement, series relay 208 falls back and opens the locking circuit of relay 202 at armature 240, whereupon relay 202 falls back and shifts the operating conductor from the vertical magnet to the rotary magnet.

When the ring-back switch receives the digit transmitted by the director in accordance with the setting of the hundreds register, Fig. 7, the impulses of current generated at armature 228 and its resting contact of line relay 203 are transmitted through armature 223 and its resting contact to the rotary magnet with the result that the wipers 244-247 are rotated into engagement with the corresponding set of bank contacts. In the present case, the ringers of the calling and called parties are both connected between the negative line and ground and they are a 50-cycle ringer and a 66-cycle ringer, respectively, as hereinbefore assumed. Accordingly, the last series of impulses includes only a single impulse and the wipers 244-247 are positioned on the first set of contacts of the level shown in the drawing. Series relay 208 is operated again during the rotary movement of the switch and it maintains the wipers

disconnected during such movement at armatures 220-242.

When relay 208 falls back, it connects up wiper 247 at armature 242, whereupon the grounded lower winding of wiper 207 is energized through armature 235 and its resting contact and armature 242 and its resting contact. The circuit of relay 207 is completed to battery over the 66-cycle ringing-current lead, which is connected to the first contact in the bank of wiper 247. Upon energizing, relay 207 completes at armature 237 a locking circuit for its upper winding to the conductor 251, grounded at armature 230; at armature 238 it opens the circuit of its lower winding; and at armature 239 it disconnects the working contact and armature 231 from the operating circuit and prepares a circuit through armature 234 and its resting contact for relay 201.

Since, according to the previous assumption, the calling subscriber hangs up before the director has finished sending, and, since the director switches through shortly after the retransmission of the last stored digit, line relay 203 shortly falls back and closes at armature 238 a circuit through armature 231 and its working contact, armature 239 and its working contact, and armature 234 and its resting contact for relay 201. Relay 201 energizes and at armature 222 completes an auxiliary holding circuit for release relay 204. At armatures 221 and 223, relay 201 disconnects conductors 94 and 96 from the windings of line relay 203 and connects them instead to armatures 224 and 227 of relay 202. Since, according to the previous assumption, both of the ringers involved in the present call are connected between the negative side of the calling line and ground the bank contact that wiper 244 is on is dead and relay 202 is deenergized, the connections in the ring back switch being such that ringing current is normally transmitted back to the negative side of the line with relay 202 deenergized. It will be noted that relay 209 is connected through armature 241 and its resting contact, and wiper 245 and the bank contact on which it is standing, with the interrupter 250. This interrupter intermittently operates the ringing-current reversing relay 209 so that it is operated during a given operation of the ringing interrupter relay 252 and is non-operated on the following operation of the said relay, etc. With relay 209 nonoperated, and with interrupter relay 252 operated, ringing current over the 66-cycle lead is placed on the negative talking conductor through bank contact and wiper 247, resting contact and armature 243, resting contact and armature 235, ring-cut-off-control relay 206, resting contact and armature 224, and the working contact and armature 221. When the ringing interrupter relay 252 is operated the next time, relay 209 is also

operated and the ringing current sent out is from the 50-cycle ringing lead through wiper 246 and the working contact and armature 243. By this arrangement, the ringers 5 at the calling and called substations are operated alternately.

When the called subscriber responds to the operation of his ringer by removing his receiver, a bridge is closed across the two conductors of the calling line, and, since the positive conductor is grounded, a circuit is closed from conductor 96, through the calling substation, and over conductor 94 for operating the ring-cut-off-control relay 206 included 15 in the ringing circuit. This relay at armature 236 closes a circuit for ring-cut-off relay 205. At armature 233, relay 205 closes a locking circuit for itself; it opens the ringing circuit at armature 235, whereupon relay 206 20 falls back; and at armature 234 it opens the circuit of slow acting relay 201 and closes a circuit for release magnet 212. Release magnet 212 energizes and restores the switch to normal, whereupon the release-magnet circuit 25 is opened at contacts 214. Slow-acting relay 201 (being slow acting so as to give the release magnet time to operate) falls back responsive to the opening of its circuit at the resting contact of armature 234. At armature 30 222, relay 201 opens the circuit of relay 204 and at armatures 221 and 223 it shifts the conductors 94 and 96 back to the windings of line relay 203 again. Line relay 203 now 35 operates over the calling line in series with the transmitter bridge at the called substation, and at armature 228 it closes a circuit for relay 204 before the same has had time to fall back.

When the calling subscriber notes that his 40 ringer has stopped operating, he removes his receiver, whereupon the conversation may take place in the usual manner.

When both subscribers have replaced their receivers at the end of the conversation, line 45 relay 203 falls back and opens the circuit of release relay 204 at armature 228, and relay 204 falls back after a slight interval and at armatures 229 and 230 removes ground from conductors 95 and 251. Relays 205 and 207 50 now fall back. At armature 231, release relay 204 closes a point in the release magnet circuit, but as the switch has already been restored to normal the release magnet circuit is open at off-normal contacts 214.

55 Responsive to the removal of ground potential from conductor 95 the preceding portion of the connection is released in the usual manner.

60 *Hang-up-tone reverting-call operation*

The hang-up-tone method of reverting-call operation will now be explained. When this method of operation is used, the terminals 215 and 216, Fig. 3 are jumpered together, with the result that when the director

has finished sending, the hang up tone is sent back over the calling line and informs the calling subscriber that he may now hang up his receiver. Also, the locking connection, Figs. 6 and 7, to conductor 46 and including 70 off-normal contacts of the hundreds register and armature 508 and its working contact is not provided, and, in Fig. 1, the conductor connected through armature 26 may be transferred to armature 25, and armature 26 and 75 its associated contacts may be eliminated.

When this modification is used, the subscribers are instructed to dial the numbers as in the previous description, but to wait for the hang-up tone before replacing the receiver. In this case it is evident that the hang up tone cannot be heard until the ring back switch has been set and until the switching through relay 23, Fig. 1 has been operated. Accordingly, the director is held up 80 from ground supplied to conductor 46 through the director selector DS, from the working contact and armature 28, Fig. 1, and when the switch-through circuit is enclosed it includes armature 25 and its working contact of relay 21, Fig. 1, as relay 21 is 85 still operated at this time.

Referring now to Fig. 3, when the ring back switch has been positioned on the necessary contacts, relay 207 is operated in the 90 hereinbefore described manner and at armature 253 connects the common hang-up tone lead through armature 252 and its resting contact, and the jumper between terminals 215 and 216, to the lower talking conductor. 95 Upon hearing this tone the calling subscriber replaces his receiver whereupon relay 203 falls back with the results hereinbefore described.

The remaining portion of the operation is 100 the same as described hereinbefore.

Simplified reverting-call operation

When it is desired to reduce the complicacy of the exchange equipment as much as possible, a still different operation may be employed. In this third case, the relay 506 Fig. 6 and its associated connections may be eliminated, the conductors passing through normally closed contacts on relay 506 being arranged so that these contacts are by-passed. In this case the bank contacts on which the wipers of the office register OR are set when a reverting call is made are connected up like the bank contact set 503. As soon as the lower 110 OCS wiper is grounded by the upper ICS wiper, after the wipers of the office register are set on this bank contact set, a circuit is closed through the first wiper of the office register, the bank contact on which it is standing the associated I.D.F. jumper, and conductor 308 for the switching relay 403, Fig. 5. When the switching relay operates, the switching relay 23 in the trunk circuit TC is 115 operated in the hereinbefore described man- 120 125

ner and the director is released. This switching operation occurs between successive digits dialled by the calling subscriber and without his knowledge, the calling subscriber being instructed to follow the two characteristic digits by the digits 3, 6, and 4, necessary to operate the switches OS, M, C and two more digits to operate a ring back switch. These switches respond directly to the control on his calling device instead of indirectly through the director as hereinbefore described.

Meter operation

The meters 407—410, Fig. 5, will now be considered. It will be noted that the meter 410 is connected between the free pole of battery and release trunk conductor 46. As a result, the meter 410 is operated each time conductor 46 is grounded responsive to the seizure of the director, and the reading of this meter indicates the actual number of times the director is seized and released regardless of the disposition of the calls responsive to which the seizures are made.

25 Meter 409 is arranged so that it is operated at armature 416 each time the switching relay 403 operates. This meter therefore gives a reading of the total number of times the switching relay 403 is operated.

30 The meters 407 and 408 are arranged to be alternatively operated by the switching relay 403, depending upon the position of relay 402. If the switching relay 403 operates because the director has completed its operation in handling a regular connection, relay 402 is not energized and meter 408 operates in multiple with meter 409. On the other hand, if the switching relay 403 operates merely to free the director on account of a delay in 35 dialing after the director is seized and either before or after a number has been partly dialed, relay 402 is in operated position and meter 407. The manner in which relay 402 operates will now be briefly explained. The

40 slow interrupter 401 is operating at a rate of speed which is slow enough to insure that ample time is allowed for dialing at least one digit between successive operations of the interrupter. The intermittently grounded lead 45 controlled by interrupter 401 is connected up at armature 414' of release relay 404 when the director is seized. As soon, after this occurs, as the conducting part of the interrupter comes under the associated brush, a circuit is 50 completed through armature 414' and its working contact and armature 411 and its resting contact for the upper winding of the two-step relay 402. When energized through its upper winding alone, relay 402 operates 55 through its first step only, operating its first-step armature 412, but not its second-step armatures 411 and 413. Armature 412 closes a locking circuit for relay 402 including conductors 306 and 307 in series with the lower 60 contacts of relay 301, Fig. 4, the conductor 65

307 being an extension of the grounded release trunk conductor 46. The lower winding of relay 402 remains short circuited, however, until the initial circuit for the upper winding is opened by the interrupter 401, whereupon the two windings of the relay 402 energize in series, operating the relay through its second step. At armature 411, relay 402 opens a further point in its initial circuit and prepares a circuit for switching relay 403, and at armature 413 it shifts armature 416 from connections with meter 408 to in connection with meter 407. It will be remembered that relay 301 operates each time a series of impulses is received by the director. If a series of impulses is received the slow interrupter 401 closes again, relay 402 falls back because its backing circuit is opened and prevents the switching relay 403 from being operated, and the previously-described operation of relay 402 is repeated when the interrupter contacts again close. However, if, at any time, no digit is received between successive operations of the interrupter a circuit is closed through armature 411 and its working contact for relay 402, switching the connection through at the trunk circuit TC in the hereinbefore-described manner and freeing the director. In this case, since armature 413 is in its alternate position meter 407 is operated instead of 90 meter 408.

95 It will be noted that either of the meters 407—409 could be eliminated, if desired, in which case the equivalent of the reading of the eliminated meter could be readily calculated from the readings of the two remaining meters. It is considered to be preferable, however, to provide the three meters as shown in the drawings, as in this way a defective reading on any meter may be discovered by comparing it with the readings of the other two.

100 It may be pointed out that the difference in the readings of meters 409 and 410 indicates the number of calls abandoned before the call has progressed sufficiently far for the director to be freed by the operation of relay 403.

105 Regarding the utility of relays 451 and 452 Fig. 5, it may be stated that these relays are provided in order to enable the cut-off of the director to be revertively controlled. When a call is made to a party line substation, an extra digit is needed to operate the station selector, for example the station selector shown in Fig. 2. Accordingly, the director is arranged so that it is automatically cut off (switches through) as hereinbefore described when the number contains a stations digit. When a call is made through a 110 connector not equipped with a station selector, however, the stations digit is omitted, and an arrangement similar to that disclosed in Fig. 8 of the copending application of Richardson et al. Serial Number 694,842, 115 120 125 130

filed Feb. 25, 1924, may be used. In this arrangement, the straight line connectors are so arranged that, when the rotary movement of the connector is terminated, current is 5 momentarily reversed in the trunk line leading to the connector. This will result in the operation of the polarized relay 452, Fig. 5, as it is shunted around the resistance 453 in the outgoing control circuit. Relay 451 is 10 operated as a result, and, when relay 452 falls back at the end of the momentary reversal, it closes through the armature of relay 451 a circuit for relay 403, with the hereinbefore described results.

15 What is claimed is:

1. In a telephone system, a plurality of ringing leads connected to different sources of ringing current, a ringing current selecting switch having a wiper and a bank of contacts arranged to be connected with said ringing leads, and means for preventing said wiper from short circuiting said ringing leads by distributing them amongst the contacts in said bank so that dead contacts are 25 left in the bank between contacts that are connected to said ringing leads.

2. In a telephone system, a trunk line, a register sender, means for connecting said trunk line with said register sender, means 30 responsive to a particular setting of the registering portion of said register sender for locking said register sender in connection with said trunk line, and means responsive to the operation of said sending apparatus under the control of said register for unlocking said register sender.

3. In a trunk circuit, a line relay, a release relay, a switching relay, a circuit for said switching relay through contacts on 40 said line relay and on said release relay when the line relay and release relay are operated, and circuit for said switching relay through contacts on said release relay alone when said release relay is non-operated.

45 4. In a telephone system, a ring-back switch arranged to be operated over a calling line and to remain operated after the receiver has been replaced on the calling line, and means including a source of tone current 50 for informing the calling subscriber when he may replace his receiver after having brought about the operation of the ring-back switch.

5. In a telephone system, automatic 55 switches for setting up a connection, means for automatically holding up the connection after the same has been established up to a certain stage, a register sender for controlling the switches, and means in said register 60 sender for holding up the connection in case the calling party hangs up before said certain stage is reached.

6. In a telephone system, automatic 65 switches for setting up a connection, means for automatically holding up the connection

after the same has been established up to a certain stage, a register sender arranged to be set by a calling subscriber for controlling said switches, a portion of such control being exercised after the calling subscriber has hung up, and means in said register sender 70 for holding up the connection in the interim between the hanging up of the receiver and the completion of the connection up to the said stage specified.

7. In an automatic telephone system in 75 which the calling subscriber hangs up his receiver to start a revertive ringing operation and in which register senders are used to set the switches involved in selecting the ringing equipment, means for giving the calling subscriber a distinctive signal to notify him when to hang up his receiver.

8. In an automatic telephone system in 80 which the calling subscriber starts the operation of a selected ringing device by an act which is only effective after the device has been selected, and in which the selection is accomplished under control of a register sender subsequent to the operation of the subscriber's 85 dial, means for notifying the subscriber when the said act is to be performed.

9. In a director for use in a party line system including reverting call apparatus, a register adapted to be set in accordance with 90 digits indicating a reverting call, and means controlled responsive to such setting for altering the director circuits to adapt the same for controlling said apparatus.

10. In a telephone system in which connections are set up under the control of a calling subscriber's calling device, means effective during the extension of a connection to hold the operated switches should the calling subscriber hang up his receiver, and other means effective after the connection is fully extended to hold up the connection after the calling subscriber has hung up.

11. In a telephone system, a ring-back 100 switch, a register sender set under the control of a party line subscriber to operate said ring-back switch to a position to ring a called subscriber on the calling line after the calling subscriber has hung up, means for locking said ringback switch in its operated position 105 only after it has been set, and means for informing the calling subscriber when the ring-back switch is set.

12. In a director for handling reverting 110 calls, means in said director responsive to a partial registration of a reverting call number for preparing a locking circuit for the director, and means responsive to the registration of the last reverting call digit for rendering said locking circuit effective.

13. In a director, two successively operable 115 registers, a locking circuit for said director, and means for rendering said circuit effective dependent upon a particular operation of the 120

130

first register and upon the second register being set.

14. In combination, a ringing-current selecting switch having two wipers and a contact bank for each wiper, a plurality of ringing leads, there being an off-normal position of said switch assigned to each of said ringing leads, half of said ringing leads being connected to alternate contacts in the bank of one wiper, the remaining ringing leads being connected to noncorresponding contacts in the bank of the other wiper so that no two adjacent contacts in the bank of either wiper are connected to ringing leads, a common return conductor connected at one end to the bank contacts in said switch not occupied by ringing leads and connected at the other end so as to form a return for the ringing current received over any one of the ringing leads, and means for maintaining said conductor open between its two ends at a time when said ringing current selecting switch is being moved over its contacts and for closing the connection between the two ends of such conductor when the switch is at rest in an off-normal position.

In witness whereof, I hereunto subscribe my name this 10th day of August, A. D., 1926.

LEONARD L. RUGGLES.
